BOTTLE

James E. Plummer, Toledo, Ohio, assignor to Owens-Illinois Glass Company, Toledo, Ohio, a corporation of Ohio

Filed July 31, 1963, Ser. No. 76,046

Term of patent 14 years

(Cl. D58—6)

FIG. 1

The back and side not shown are the same as the front and side shown, with the exception that the small circle on the front does not appear on the back. The dominant features of my design reside in the portion shown in full lines.

I claim:
The ornamental design of a bottle, substantially as shown and described.
